E. S. MATTHEWS

ELECTRIC ELEVATOR CONTROL SYSTEM

Filed March 12, 1923

UNITED STATES PATENT OFFICE.

EDWIN S. MATTHEWS, OF NEW YORK, N. Y.

ELECTRIC ELEVATOR-CONTROL SYSTEM.

Application filed March 12, 1923. Serial No. 624,399.

The object of this invention is the provision of means to assist persons operating elevators to stop the car within prescribed limits of close proximity to the various landings which it serves.

It is particularly useful in passenger elevators but its use is not restricted thereto.

Frequently in busy passenger elevators the car is so crowded with passengers as to prevent an operator from properly seeing the landing as he approaches it, thus preventing the most skillful and conscientious operator from shutting off the power at the right time to properly stop the car.

In the case of electric elevators, suitable control of the speed of the car while running under power, and just before it is brought to rest with a diminishing sliding motion due to brake retardation causes the ensuing stop to be made with a good degree of accuracy.

Hence this invention is particularly adapted to be used in connection with the speed control of an elevator whose motor is operated in the manner set forth in my United States Patent No. 1,490,673 issued April 15, 1924, where all the details of a system of control for elevator motors are set forth.

However, its use is not restricted to that system of control but it may be used with any practical system of elevator motor control, many of which are well known and for this reason the details of switches, circuits, etc., of such a system are not set forth in this application.

Automatic stops acting for one direction of car travel only and cooperating with and superseding the usual operator's elevator controlling mechanisms are in common use for terminal landings; but this invention provides the operator with a supplementary manually controlled stop acting in either direction of travel for any or intermediate landings which he can use or not as he chooses and in the way he chooses, and which does not supersede the usual control which latter is usable by the operator at all times, leaving him at liberty to stop the car at the landing by his usual car controlling mechanism without bringing the supplementary stop into action if he so desires.

To stop the car of an electric elevator exactly at a given point it is necessary to shut off the motive power at exactly the right point in its travel, from which point the car slides onward under retardation of the brake and other forces until it comes to rest, as is well known.

Automatic landing stops for electric elevators heretofore in use have shut off the power arbitrarily as a result of car motion, at some given point determined by car location, in the travel of the elevator.

Now the retarding forces in effect during the sliding stop of an electric elevator are variable, and particularly the frictional resistance of the brake, cables, etc., varies according to the condition and state of adjustment of the apparatus, and the extent to which it is "limbered up".

The method of operating a landing stop for electric elevators, by causing the motion of the car to effect the shutting off of the power at a variable point in the travel of the elevator according to the amount of sliding the elevator will subsequently do in coming to a stop now set forth in this specification, is broadly new, as far as the applicant is aware.

In this embodiment of that feature of this invention the operator varies the above mentioned point according to his observation and knowledge of the sliding conditions of the elevator car at the time the stop is to be made; and, since by the use of this invention, he does not need to see his landing in order to find it or make it properly, (as will become manifest) he is enabled to closely watch sliding conditions and rightly allow for them.

Other features and objects of this invention will become manifest to those skilled in the art as its typical embodying instrumentalities and its operation are later explained, and its novel features are pointed out in the claims.

The exemplifying structure herein shown is illustrated by a diagrammatic drawing, usual conventionalities being employed, and this structure and its operation will now be described in detail, reference being had to the drawing, in which:

Fig. 1 shows an elevator machine with a controller connected thereto located above

an elevator car which is suspended from the machine in a well known manner, two typical landings of the elevator hatchway with exemplifying contact plates for each 5 landing, operating switches on the car with wiring connections thereto and to the contact plates and controller of the elevator machine; which may be operated directly through the direct line of wiring, at the 10 right of the conducting plates or otherwise if desired in an alternative indirect manner by a sparkless relay shown in the upper left portion of this figure, through wiring connections, shown at the left of the conducting 15 plates.

Fig. 2 shows a transverse section of the operating switches on the side of the car, and of the hatchway and typical contact plates of one of the landings in their relative positions when the car is level with the landing as shown in Fig. 1.

Fig. 3 is an enlarged drawing of the typical landing contact plates.

Current supply enters the apparatus at the 25 signs + and - at the right hand side of the drawing.

10 represents an elevator car and 11 a pivoted lever or car switch for manually controlling the apparatus mounted upon an 30 insulating control board or upon the side of the car itself if formed of insulating material as shown, which has a slot 13 of definite length cut through it which extends through the side wall of the car at that point.

35 This slot is preferably curved on a radius from the pivot point 14 of the car switch lever and of a width sufficient to permit the push button stem 15 carrying + current to pass freely through it, and of a length sufficient to permit a considerable swing of the car switch while the push button stem is protruding through the slot, but not long enough to permit the car switch, at such times to make connection with either car 40 running contact 16 or 17 which are respectively the up and down motion contacts for operating the car with the speed in use just before the supply to the motor armature is severed for making the necessary sliding stop 45 which brings the car to rest.

This car switch may also have higher speed contacts more remote from the center than 16 and 17 but as they are not material to this invention they are not herein described.

18 represents the electric hoisting, lowering and sustaining machine (of the traction type) by which the elevator is operated; having a traction sheave, motor, friction 50 brake and other appurtenances and parts well known in such machines.

19 represents a cable or cables sustaining the car and counterweight 20, being attached thereto and governed in position by their 55 contact with the traction sheave of 18.

21 represents the enclosed elevator controlling board provided with switches, resistances, etc. for operating the apparatus, such for example as that shown in U. S. Patent No. 1,490,673 issued April 15, 1924, 70 from which conductors proceed to the motor through conduit 22.

23 and 26 represent two intermediate landings served by the elevator car, although the constructions and mode of operation 75 herein shown is applicable to terminal landings; in which case the full automatic terminal stop of the apparatus is arranged to occur at a point a little beyond such terminal landing; and is used as an emergency stop 80 only.

24 and 25 represent two insulated conducting plates attached to the hatchway, close to the car as it moves by them, and in a plane parallel to that motion and to the swing of lever 11; being located so that when push button stem 15 is pushed outwardly by the operator it will make contact with these plates when opposite to them. They are located with an aperture between them arranged so that when the car is as near the landing as may be required and the lever 11 is in central position with the stem 15 pushed toward the plates as far as possible it will not make contact with either plate; but if the car is too high above the landing contact will be made with plate 24 and if too low from the landing contact will be made with plate 25.

27 and 28 are corresponding conducting plates for landing 26, and all landings where it is desired to operate this apparatus are provided with similar plates, similarly arranged with reference to the landing and their electric connections are also similar.

The aperture between these contacting plates is greater at their side edges than at their center (see plates 27 and 28) and is so arranged that the maximum vertical length of possible contact of push button 100 15 with either plate gradually diminishes as it is swung from center position in either direction, the extent of this motion being limited by slot 13; as is shown by dotted line 29 105 representing the arc of motion of push button 15.

In each of these plates a groove is cut on this arc of motion so located that when the pushed in push button stem reaches it, in course of the motion of car toward the landing, the operator can feel the groove (although it does not affect the electric circuit) and thus learn that the car has approached nearly to the landing whether he can see the landing or not.

This push button stem 15 moves longitudinally through a hole in the center of the operating handle and is held normally pushed back from contact with the conducting plates 24, 25, 27, 28, etc., by the spring 110 115 120 125 130

40; so that the force necessary to make such a contact is supplied by the operator, and in this embodiment of the invention he must continually force 15 against the plate while 5 floor finding by means of this apparatus is in progress, hence he readily feels the passage of 15 over the grooves 39, although these grooves may be omitted if desired, as they are not a necessity to the operator and 10 floor finding is accomplished satisfactorily without them.

Other means may be used to apprise the operator of the location of the car relative to an unseen landing, and the electric circuits and means herein shown may be modified for the use of an operator who is not located in the elevator car without departing from the spirit of this invention.

As herein illustrated the lowest speed of 20 the ordinary car switch control is used in floor finding, and when this speed is dependable for such purpose as in the system of motor control shown in U. S. Patent No. 1,490,673, issued April 15, 1924, this is a preferred arrangement; but in the case of some 25 existing motor control systems the lowest car switch speed cannot be depended upon for floor finding work.

In such cases the conducting plates are 30 wired by separate individual leads, not connected with the car switch leads, to the starting, reversing and stopping switch of the slow speed floor finding power apparatus which may be provided from the Ward 35 Leonard System, a multi-voltage system, dynamotor system, or auxiliary motor system; the only necessity being that such power apparatus shall fulfill the rudimentary requirements of dependability, reversibility, 40 of being brought into action and of being stopped by an electric switch, and of holding the load when stopped.

The operation of the herein described apparatus will now be explained and in that 45 connection the electric circuits which are of a simple character will be described in detail.

Two sets of electric circuits are shown, one for direct operation shown at the right 50 of the conducting plates and the other for induction neutralizing sparkless relay operation shown at the left of the conducting plates, either one of which systems may be used.

55 As shown in the drawing the car is at the landing 23 and no circuit is in use in the direct operation system and only the holding circuit of the relay system if that system is in use, instead of the other.

60 The direct operating system will be first described after which the relay system will be readily understood.

In case the elevator is operated to go from 65 landing 23 to landing 26 and the latter is made by the floor finding system, no atten-

tion is paid to the push button 15 by the operator at the start.

The operator's switch 11 is moved so as to connect it with contact 17 and also higher speed contacts beyond it (not shown in the drawing being immaterial to this invention) and the car moves downward the electromagnetic reversing and current supply switch of the elevator motor being properly operated by the current from + through 75 wire 30 contact 17, wire 34 and wire 32 leading to the down motion switch coil, thence through wire 41 to the - main. Motor supply is from + through wire 29, conduit 22, the motor, conduit 22 and wire 80 41 to the - main.

As the car approaches landing 26 the operator moves his switch 11 toward central position releasing contact 17, presses in 85 push button stem 15 making contact with plate 27 which causes the elevator to run on its downward slow adjusting speed as long as he continues his pressure of 15 until by the continued motion of the car, contact 15 runs off plate 27 cutting off the power 90 and stopping the car. If he keeps his car lever in exactly central position this contact will be maintained and the circuit through wire 32 continued until the car stops exceedingly close to the landing 26 if 95 not exactly at it, with a light load in the car, and prompt and efficient brake action.

If, however, the car is heavily loaded and the brake is in inefficient condition causing an excess of slip in stopping the car, the 100 operator upon pressing 15 will keep his lever as far from the center as the construction permits thus causing the push button contact 15 to run off the plate 27 as soon as 105 possible, consequently cutting off power and applying the brake at the earliest moment the nature of the floor finding apparatus will permit.

The result is that the car stops near or at 110 the landing. If the stop is satisfactory he releases the push button.

If he brings his lever to the center while maintaining his pressure on the push button, there will be no result if the car is exceedingly close to the landing.

If not, the push button 15 will again make contact with a conducting plate, and the farther the car is away from proper position the more quickly such a contact will be made.

If in this manipulation of the apparatus the car is below the landing but not sufficiently so to bring the pushed button in contact with upward car moving conducting plate 28 while the lever 11 is remote from 115 its central position, the bringing it to or towards center position will cause pushed button 15 to make contact with plate 28 and the car to move upwardly at slow speed 120 toward the landing and since upward car 125 130

movement causes 15 to run off of plate 28 the car in such case is brought by the operator exceedingly close to the landing.

If the operator happens to incorrectly assume too great a sliding for his car, and while pushing the floor finding button 15 erroneously keeps his lever 11 too remote from the center, he will stop short of proper position for that landing; but he instantly corrects this by bringing his lever to the center, again making onward running contact and consequently then stops correctly.

The circuit for the downward car moving 13 conducting plate 27 proceeds from the + main wire 30, lever 11, pushed button 15, plate 27, wire 38, wire 32 leading to the proper down motion reversing switch coil thence through wire 41 to the - main.

20 The circuit for the upward car moving conducting plate 28 is from the + main wire 30, lever 11, pushed button 15, plate 28, wire 37, wire 31 to the proper up motion reversing switch coil, thence through wire 41 to the - main.

All upward and downward car moving conducting plates including 24 and 25 are connected in a similar manner.

The circuits for induction neutralizing 23 sparkless relay operation of this apparatus are shown with the coils and switches for the same at the left of the elevator car in the drawings.

When this apparatus is used in place of 25 the direct operation heretofore described, the switch having contacts 42 and 43 brings into action the upward moving slow floor finding speed of the apparatus, through the same switches as the direct operation uses, whenever these contacts are closed by gravity action;—or stops its operation when they are separated by magnetic action as shown in the drawings; and switch with contacts 44 and 45 similarly controls the downward 49 moving slow floor finding speed. Contacts 42 and 44 are both connected to the + supply from wire 49 through wire 46. Coils 47 and 48 are in constant circuit from + supply through wires 49 and 50 and to the 55 - main 41 by wires 51, 52 and 53 and their magnetic excitation holds their respective switches open as shown in the drawing, since coils 54 and 55 are not excited in the position of elevator apparatus shown in the drawings. Coils 54 and 55 are of opposite polarity to coils 47 and 48 with which they are respectively associated and when 47 is excited the double coil 47, 54 loses all magnetism, and double coil 48, 55 operates in the same manner. Hence when coil 55 is excited contact 45 falls into contact with 44, and when 54 is excited contact between 43 and 42 is made in a similar manner.

Coil 55 is connected to all downward car 65 moving conducting plates by wires 56 which

connects to plate 24 from which wires lead to all similar plates as is now understood from which + electricity is received by this coil whenever pushed button 15 contacts with any such plate as heretofore described, and 70 the circuit is completed through wires 57 and 53 to the - main 41.

Coil 54 is similarly connected to all downward car moving conducting plates being connected to plate 25 through wire 58, and 75 to - main through wire 53.

It is now obvious that these switches act as relays in accomplishing the results of the direct connections from all conducting plates, and that there can be no inductive sparking 89 when pushed button 15 leaves any conducting plate from any circuit through either relay double coil 47, 54 or 48, 55.

The actuating electro-magnets for the slow power reversing switches, operated by the 85 direct operation system, are preferably constructed in the same manner as these heretofore described for the relay system operation; thus avoiding sparking at actuating contacts in the use of that system. 90

In such case the regular reversing switch multiple contacts with their proper leads to the motor are substituted for the single contacts 42 to 43 and 44 to 45.

Many variations in the construction and 95 details and location and arrangement of parts would readily suggest themselves to those skilled in the art to which this invention relates and still fall within the spirit and scope of my invention; hence I do not desire to be limited to the exact construction herein set forth; but having explained the principles of my invention and a preferred form of apparatus embodying it, and 100

Having described the function, purpose, 105 and mode of operation of such apparatus what I claim is new and of my own invention, and desire to secure by Letters Patent of the United States is,—

1. In an electric elevator the combination 110 of the car, a hoisting, lowering, starting, stopping and sustaining electric motor machine, electric means to control the operation of said machine, with additional means constructed and arranged to be operable manually at all times when the car is in the region of a landing, but not at it, to stop or start said machine; and further controllable, as to direction of car motion which may be imparted from said machine, by the 115 position of the car with reference to the landing, when in its region but not at the landing, and also controllable to stop the car at the landing only by the action of the operator or the joint action of the operator 120 and the movement of the car.

2. In an electric elevator the combination 125 of the car, an electric hoisting motor, electric means to control the motor, controllable unitedly by the position of the car, and a 130

- manually operated switch constructed and arranged to cause the car when said switch is manually operated while the car is in the region of, but not at a landing through the 5 operation of the motor to approximate to and later stop at said landing from either direction, which stop incapacitates said switch from action while the car remains at said landing.
- 10 3. In an elevator the combination of a car, a motor having a running speed and a slower adjusting speed, a car switch for controlling the running and adjusting speed operation of the motor, and a supplementary car switch for bringing into action or cutting out of action the adjusting speed of the motor, only after the first-named car switch has relinquished its control of the motor.
- 15 4. In an elevator the combination of a car, a motor having a running speed and a slower adjusting speed, a car switch for controlling the running and adjusting speed operation of the motor, a supplementary car switch for bringing into action or cutting out of 20 action the adjusting speed of the motor, only after the first-named car switch has relinquished its control of the motor, and a contact for said switch determining the direction of motor rotation according to the position of the car in the hatchway.
- 25 5. In an elevator the combination of a car, a motor having a running speed and a slower adjusting speed, a car switch for controlling the running and adjusting speed operation of the motor, a supplementary car switch for bringing into action or cutting out of 30 action the adjusting speed of the motor, only after the first-named car switch has relinquished its control of the motor, and contacts separated by an interval of insulation for determining opposite directions of motor rotation as the supplementary switch passes by this 35 interval in the motion of the car.
- 40 6. In an elevator the combination of the car, an elevator motor therefor, controlling apparatus therefor, including means operating to stop the car near some fixed point in its extent of travel as a result of its own motion, with means controllable by the operator constructed and arranged for manually varying the proximity to said 45 fixed point at which such stopping means operates.
- 45 7. In an electric elevator the combination of the car, an electrically operated motor therefor, electric means to control the motor, including means for controlling an electric circuit by making or breaking the same so as to stop the motor as a result of the motion 50 of the car when the latter is near some fixed point in its extent of travel with means controllable by the operator constructed and arranged for manually varying the proximity to said fixed point at which the 55 breaking of said circuit occurs.
8. In an elevator, the combination of the car, motive and controlling means for raising, lowering, starting, stopping and sustaining the car, with an operator controlled switch effective for starting, stopping or continuing the motion of the car only when it is in the region of a given fixed point in its travel but ineffective to cause any car motion when the car is substantially at said fixed point.
- 70 9. In an elevator, the combination of the car, motive and controlling means for raising, lowering, starting, stopping and sustaining the car, with an operator controlled switch effective for starting, stopping, or continuing the motion of the car only when it is in the region of a given fixed point in its travel and causing it to move toward said given fixed point only.
- 75 10. In an elevator, the combination with the car of means constructed and arranged to give the operator opportunity to become aware of the proximity of an approaching car to its coming landing, independently of visual observation, said means being operative only in the off position of the controller member.
- 80 11. In an elevator, the combination of the car, motive and controlling means for raising, lowering, starting, stopping and sustaining the car, with an operator controlled switch effective for starting, stopping or continuing the motion of the car only when it is in the region of a given fixed point in its travel, and causing it to move toward said given fixed point only, but ineffective to cause any car motion when the car is substantially at said given fixed point.
- 85 12. In an elevator, the combination of the car, motive, sustaining and controlling means therefor, with two manually operable controlling switches which are operable separately but not unitedly; one of which is effective to stop or start the car in any position which it may occupy in its extent of travel, while the other is operative only to cause the car to approach a neighboring landing, and to stop the car wherever desired in such approach, but having no control over car motion when the car is substantially at the landing.
- 90 13. In an elevator, the combination of the car, motive and sustaining apparatus, controlling means therefor comprising an electro-magnetically operated switch for starting, stopping or continuing the motion of said car, the actuating coil of said switch being provided with a circuit constructed, arranged and connected so as to be governed by the position of the car in the hatchway 100 as to the possibility of said circuit being made or broken, and means to prevent arcing when said circuit is broken.
- 105 14. In an elevator, the combination of the car, motive and sustaining apparatus, con-

trolling means therefor comprising an electro-magnetically operated switch for starting or continuing the motion of the car only to cause the car to approach a neighboring landing, or for stopping said car, the actuation coil of said switch being provided with a circuit constructed, arranged and connected so as to be governed by the posi-

tion of the car in the hatchway as to the possibility of said circuit being made or broken, and means to prevent arcing when said circuit is broken. ¹⁰

In testimony whereof, I have signed my name to this specification.

EDWIN S. MATTHEWS.
